UNITED STATES PATENT OFFICE.

ALBERT MANNING BRAY, OF CLEVELAND, OHIO.

INTERNAL-COMBUSTION ENGINE.

Application filed September 23, 1921. Serial No. 504,624.

To all whom it may concern:

Be it known that I, ALBERT M. BRAY, a citizen of the United States, residing at Cleveland, in the county of Cuyahoga and State of Ohio, have invented a new and useful Internal-Combustion Engine, of which the following is a specification.

This invention relates to internal combustion engines, and is more particularly directed to an engine of the two-cycle type adapted for use in automobiles, aeroplanes, or for marine propulsion, and likewise for tractors, trucks and as a stationary engine.

It is an object of the invention to provide a new and improved engine of the two-cycle type wherein an auxiliary piston is employed in the power cylinder to compress the charge of gas in advance of its admission to the combustion chamber. The compression chamber is located in the power cylinder between the lower head of a double-headed power piston and the compression piston, and is of so much greater capacity than the combustion chamber, that the pressure within the compression chamber will properly counterbalance the weight of the longer and heavier connecting rods of the power piston. The compressed combustible gases from the compression chamber entering the combustion chamber with some force will properly scavenge said chamber. The lower head of the power piston is of a greater area than the upper head for the purpose of drawing into the compression chamber a greater volume of gas to be compressed than the combustion chamber is capable of normally holding.

The relative positions of the exhaust and intake valves of both the combustion chamber and the compression chamber, with respect to the movements of the two pistons, are such that not only is a well balanced structure obtained, but a perfect working mixture and scavenging is accomplished.

Furthermore, a new and improved form of wrist pin is provided whereby certain advantages result, when employing two connecting rods for the power piston, which have not heretofore been obtained, especially when the engine is constructed in multiple.

The invention will be best understood from a consideration of the following detailed description taken in connection with the accompanying drawings forming part of this specification, with the understanding, however, that the invention is not confined

to any strict conformity with the showing in the drawings, but may be changed and modified so long as such changes and modifications mark no material departure from the salient features of the invention as expressed in the appended claims.

In the drawings:

Fig. 1 is a vertical transverse section of the engine.

Fig. 2 is a vertical section taken along the line 2—2 of Fig. 1.

Fig. 3 is a transverse section taken along line 3—3 of Figure 1.

Figs. 4 and 5 are diagrams showing the various positions of the pistons during the two cycles of the engine.

Referring to the drawings, 1 designates supports of the engine integrally formed with the crank case 2 by which the engine may be secured in place. The crank case is provided with the usual plug 3 which, when removed, is adapted to drain the crank case. Perforated ears 4, integrally formed with and projecting outwardly from the crank case, are adapted to aline with complementary perforated ears 5 on the housing 6 for securing said housing of the engine to the crank case by means of bolts 7.

Rotatably mounted in the bearings 8 in the crank case is a crank shaft 9 provided with the usual fly-wheel 10 upon its outer end, and with a pair of cranks 11 and a single crank 12, which is advanced at an angle of 85° from the cranks 11. Within the housing 6 and cast integrally therewith is a stepped cylinder 13, providing a combustion chamber 14 between the upper end of the stepped power piston 15 and the cylinder head 16.

The power piston 15 is provided between its stepped portions with a diametrically disposed wrist pin bearing 17, through which are inserted from the opposite ends thereof the members 18 and 19 forming a two-piece wrist pin. The members 18 and 19 of the wrist pin are provided with an enlarged portion 20 forming shoulders slidable in the slots 21 and 22 of the cylinder 13. These members are also provided with reduced portions 23 upon which are journaled the upper ends of the connecting rods 24 and 25, (Fig. 3). Beyond these reduced portions are threaded ends 26 upon which are screwed nuts 27 for maintaining the connecting rods 24 and 25 upon the ends of the wrist pins. The inner end 28 of the wrist

pin is also reduced and externally threaded and adapted to be screwed into the internally threaded socket on the inner end of the member 19. The shoulders of the enlarged portions 20 are in abutting relation with shoulders formed on the bearing.

The connecting rods 24 and 25 are coupled at their lower ends to the cranks 11.

The compression piston 30 has a wrist pin 31 diametrically disposed within a bearing 32, the hollow wrist pin 31 passing through the bared upper end of the short connecting rod 33 which, at its lower end, connects the piston 30 with the crank 12 on the crank shaft 9.

The piston 30 operating in the lower end of the power cylinder 13 is provided with a concave head or cup-shaped head 34, which forms with the lower end 35 of the power piston 20 ton and within the cylinder 13, a compression chamber 36, into which is adapted to be drawn a charge of combustible gases by the power piston 15 upon its upward stroke, from the intake manifold 37, through intake port 38 formed in the lower end of the cylinder, and through the conduit 39 extending from the side of the piston 30 to the central portion of the concave head 34.

The diameters of the lower head 35 of the power piston 15 and the head 34 of the compression piston are equal, but the diameter of the upper head 45 of the power piston is much less than the lower head 35. The difference in diameters of the upper and lower heads of the power piston causes the power piston to draw into the compression chamber 36 a greater volume of gas than its combustion chamber 14 is capable of holding. The gas in the compression chamber is compressed and forced into the combustion chamber, thus giving more power and creating more than 100³ volume in the firing chamber.

A fuel discharge port 40 for the compression chamber 36 is formed in the lower end of the cylinder 13, and upon the same side and in alignment with the intake port 38, and it connects the compression chamber 36 with a discharge conduit 40' that extends upwardly alongside of the cylinder 13, being formed integrally therewith, and is provided with an intake port 41 for the combustion chamber 14. The ports 38, 40 and 41, and the conduit 40' are along the same side of the engine cylinder and in the same vertical plane, and may be described as a transfer manifold.

An exhaust port 42 is disposed diametrically opposite the intake 41, but is of a larger diameter than the intake port 41, so that it will be opened by the power piston 15 slightly before the opening of the intake port and also be closed later than the said intake port. The power piston will therefore begin to close the intake port 41

sooner than the exhaust port 42. The exhaust port 42 is connected with an exhaust pipe 43 for directing the exhaust gases from the engine.

A baffle 44, formed upon the piston head 45 of the power piston 15, is adapted to direct the incoming gases from the port 41 upwardly and around the cylinder head 16, in order to more thoroughly scavenge the combustion chamber upon the intake stroke of the engine.

Diametrically disposed plugs 46 screwed into openings in the upper portion of the housing 6 and adapted to come into alignment at certain times with the nuts 27 on the ends of the wrist pin members 18 and 19, provide ready access to the same for removing the wrist pin members. The pipe 47 supplies water jacket 48 with a fluid for cooling purposes, a portion 49 of the water jacket being shown in cylinder head 16.

The spark plug 50 projects through an opening in the cylinder head for igniting the combustible gases.

The operation of my device is as follows:—

As shown by Figures 4 and 5, Fig. 4 represents the movement of the compression piston 30, while Fig. 5 represents the movement of the power piston 15. W in both cases represents the position of both pistons, when the power piston is at its lower dead center. Starting with the power piston at the bottom of its stroke, shown in Fig. 5 at W, that is the lower dead center, the compression piston 30, by reason of the position of the crank arms 12, is located 85° in advance of the power piston 15, shown in Fig. 4 at W, and therefore is within 5° of completing half of its upward stroke, the intake port 41 and the exhaust port 42 of the combustion chamber both being fully open. The port 38 is about to be uncovered by the compression piston 30, while the port 40 is closed. The continued upward movement of the power piston 15 causes a vacuum in the compression chamber 36, and as the upward movement of both pistons is simultaneous, the port 38 will open just beyond the point of the upper half stroke of the compression piston, shown at W'. Fig. 4, when the power piston will draw in combustible gases from the intake manifold 37, the port 40 having been closed by the compression piston so that no more combustible gases will escape from the compression chamber 36. At this time, the power piston will have advanced sufficiently to close the exhaust and intake ports and compress a charge of combustible gas in the combustion chamber.

When the compression piston 30 has reached its upper dead center, the port 38 is entirely open, as shown at X in the diagram, Fig. 4, and also in Fig. 2, while the power piston is still advancing and enlarg-

ing the compression chamber 36 and drawing a volume of gas into the compression chamber, which is greater than the volume of the combustion chamber, and thereby 5 supplying a sufficient amount of combustible gas to the combustion chamber and also thoroughly scavenging the same, when the ports 40, 41 and 42 have been opened, which occurs later in the cycle.

10 The power piston 15, as shown in the diagram of Fig. 5, by the letter X, is on its upward stroke. The compression piston 30, having reached its upper dead center at X, Fig. 4, is now starting upon its downward stroke, closing the valve 38 at that point of its cycle designated by the letter Y in Fig. 4, while the power piston is about to begin its descent (its position being designated by Y in Fig. 5), when it will 15 slightly compress the combustible gases in the compression chamber 36. Gases which have been previously forced into this combustion chamber are compressed and exploded by the spark plug forcing the power piston downwardly. Beyond this point the port 40 opens and the piston forces the gas out of the compression chamber into the conduit 40', still compressing it slightly in 20 the compression chamber and in said conduit until the power piston 15 descends sufficiently to open the port 41, when the gases rush into the combustion chamber. Nevertheless, before the port 41 is open, the exhaust port 42 has been opened, permitting 25 the exhaust gases to rush out of the combustion chamber before the combustible gases are admitted. The baffle 44 directs the combustible gases upwardly around the cylinder head and thoroughly scavenges the 30 combustion chamber of the remaining exhaust gases. When the compression piston has reached its lower dead center, shown at Z, Fig. 4, the port 40 is wide open and on its return stroke will begin to close the same. 35 The power piston will have passed beyond half of its downward travel, shown at Z, Fig. 5, and its continued descent will force the remaining combustible gases from the compression chamber into the combustion chamber under compression. The compression piston will have traveled 85° from its lower dead center to the point designated by W Fig. 4, when the power piston has 40 reached its lower dead center, designated by W Fig. 5, and on its return stroke will begin to close the exhaust port and then the intake port 41, while the port 40 of the compression chamber will be closed by this time and the admission port 38 to the compression chamber will be opened by the compression piston, thereby permitting the head 45 of the power piston to draw into the compression chamber a fresh charge of gas from the intake manifold 37.

48 Just before the power piston reaches the

upper dead center, the gases in the combustion chamber are ignited which will again cause the down-stroke of the power piston, and this ignition occurs at every revolution of the crank shaft, or during two 70 cycles of the engine. It will be noted that the upper piston 15 controls ports 41, 42, while the lower piston 30 also controls two ports, viz. 38 and 40.

What is claimed is:—

75

1. In an internal combustion engine, a cylinder having a combustion chamber at one end, a compression chamber intermediate said cylinder, a double headed piston cooperating at one end with the combustion 80 chamber, a compression piston cooperating with the other end of the first-mentioned piston to compress the fuel charge within the compression chamber, means for subsequently introducing the fuel charge into the combustion chamber, a wrist pin extending diametrically through the first-mentioned piston, said cylinder having opposed slots through which the ends of the wrist pin project, a crank shaft having connecting 85 rods outside the cylinder on opposite sides thereof connecting the shaft to the ends of said wrist pin, and an intermediate connecting rod connected centrally to the compression piston.

25

2. In an internal combustion engine, a stepped cylinder having a combustion chamber at one end, a double headed stepped power piston reciprocating in said cylinder, a compression piston cooperating with the 100 end of the power piston remote from the combustion chamber to form a compression chamber, a crank shaft having two cranks, and rods connecting the cranks to the respective pistons, the crank connected with the 105 compression piston being in advance of the other crank.

105

3. In an internal combustion engine, a stepped cylinder having a combustion chamber at its small end, a stepped piston 110 operable in said cylinder, and a second piston operable in the larger end of the cylinder and cooperating with the larger end of the first-mentioned piston to compress fuel charges therebetween, and means for subsequently introducing the charges into the combustion chamber.

115

4. In an internal combustion engine, a cylinder having a combustion chamber at one end, a double-headed piston cooperating 120 at one end with the combustion chamber, a compression piston cooperating with the other end of the first-mentioned piston to compress fuel charges therebetween, an inlet port opening into the cylinder in the path of the compression piston, a passageway through the compression piston having one end opening centrally of the piston head into the compression chamber and its other end adapted to uncover said port when the 125

130

piston reaches one end of its stroke, and means for introducing the fuel charge into the combustion chamber after it has been compressed between the pistons.

5. In an internal combustion engine of the two-cycle type, a cylinder provided with a combustion chamber, a power piston, a compression piston, a compression chamber maintained in the cylinder between the two pistons and of greater diameter than the combustion chamber, means for operating the pistons simultaneously in the cylinder, the compression piston being operated in advance of the power piston, an intake port to and an exhaust port from the combustion chamber controlled by the power piston, an intake port to and a fuel discharge port from the compression chamber both opened in advance of the intake port to the combustion chamber and controlled by the compression piston, the intake port to the compression chamber being closed substantially 85° in advance of the intake port to the combustion chamber.

6. In an internal combustion engine of the two-cycle type, a cylinder provided with a combustion chamber, a power piston, and a compression piston movable relatively to the power piston, a compression chamber maintained in the cylinder between the two pistons and of greater capacity than the combustion chamber, and means for operating the pistons simultaneously in the cylinder, the compression chamber varying in volume throughout the cycles of the engine.

7. In an internal combustion engine of the two-cycle type, a cylinder provided with a combustion chamber, a power piston, and a compression piston of larger diameter than the power piston and movable relatively thereto, a compression chamber maintained in the cylinder between the two pistons and of greater capacity than the combustion chamber, and means for operating the pistons simultaneously in the cylinder, the com-

pression chamber varying in volume throughout the cycles of the engine, and having its greatest capacity during the first cycle of the engine from the upper dead center of the compression piston to 85° of 50 its down stroke.

8. In an internal combustion engine of the two-cycle type, a stepped cylinder provided with a combustion chamber and a variable compression chamber of greater 55 diameter than the combustion chamber, a power piston operating in said cylinder, and a compression piston operating in advance of the power piston and adapted to vary the volume of the compression chamber. 60

9. In an internal combustion engine of two-cycle type, a stepped cylinder provided with a combustion chamber and a variable compression chamber of greater capacity 65 at all times than the combustion chamber, a double-headed power piston operating in said cylinder and a compression piston operating in advance of the power piston and adapted to vary the volume of the compression chamber, said compression chamber 70 being defined by the wall of the cylinder and the inner ends of the pistons.

10. In an internal combustion engine of the two-cycle type, a stepped cylinder provided with a combustion chamber and a variable compression chamber of greater capacity 75 at all times than the combustion chamber, a double-headed power piston, and a compression piston operating in advance of the power piston and adapted to vary the volume of the compression chamber, the lower head of the power piston being of larger diameter than the upper but equal to the diameter of the compression piston and forming with the compression piston 80 the compression chamber in the cylinder.

In testimony, that I claim the foregoing as my own, I have hereto affixed my signature.

ALBERT MANNING BRAY.
